UNITED STATES PATENT OFFICE.

EVERETT H. BICKLEY, OF DETROIT, MICHIGAN. ASSIGNOR TO MOTOGRAPH COMPANY OF AMERICA, OF DETROIT, MICHIGAN, A CORPORATION OF MICHIGAN.

PERFORATING-MACHINE.

1,109,565.

Specification of Letters Patent. Patented Sept. 1, 1914.

Application filed December 28, 1912. Serial No. 738,546.

To all whom it may concern:

Be it known that I, EVERETT H. BICKLEY, a citizen of the United States, residing at Detroit, county of Wayne, State of Michigan, have invented a certain new and useful Improvement in Perforating-Machines, and declare the following to be a full, clear, and exact description of the same, such as will enable others skilled in the art to which it 16 pertains to make and use the same, reference being had to the accompanying drawings, which form a part of this specification.

This invention relates to perforating machines and has for its object, a machine for 15 perforating ribbons or tape.

It is designed especially for perforating ribbon used for the operation of an electrical display, as a "motograph", such as is described in my Patent No. 1,050,203.

20 The particular features and the novel arrangements will more fully appear in the detailed description following.

In the drawings:—Figure 1, is a top plan view of the machine. Fig. 2, is a side elevation, Fig. 3, is an end elevation, the supporting table being shown in section. Fig. 4, is a diagrammatic view of the pattern disk, its control, and the electric magnets that operate the punch setters. Fig. 5, is a 25 plan view, showing how the punches perforate the ribbon. Fig. 6, is a view of a portion of the pattern disk. Fig. 7, is a side elevation of the pattern disk and its control, showing them in connection with the contacts that operate the magnets. Fig. 8, is a 30 detail showing the mounting of the pattern disk, and its capability of springing up. Fig. 9, is a plan view of the pattern disk, one of its control members, and adjacent 35 mechanism. Fig. 10, is a top plan view of the contacts which are operated by the pattern disks, and adjacent parts. Fig. 11, is a side elevation of the plugs with which the contacts have a sliding engagement. Fig. 40 45 50

Fig. 12, is a cross section through the machine showing in elevation the cutting mechanism and the magnet that sets this in operative position. Fig. 13, is a side elevation of the same mechanism, portions being broken away for the purpose of clear illustration.

In my previous application there is described switching mechanism for controlling an electric display. This display is called a "motograph", meaning a moving representation. This representation or character

may be a literary character or other symbol and it is caused to appear on the display board and to move across the display board from left to right. By employing a plurality of characters any given message may be 60 caused to appear in intelligible or readable form upon the electrical display board. Hence sentences and whole paragraphs of reading matter may be caused to be thrown upon the display board and travel there- 65 across at a speed about equivalent to the rapidity of perception of an observer. These effects can be caused by a perforated insulating ribbon which travels across a field of electrical terminals. The perforations on 70 this ribbon are usually of about the same arrangement as the letter or character appearing upon the display board.

It is the purpose of my machine to perforate the ribbon for controlling the display 75 board.

A, is the table upon which is supported the major part of the apparatus. The rolls 1 and 2 (Fig. 12) are rotatably mounted above the table and between these passes the ribbon R. A pair of blocks 3 and 4 are arranged beneath the rolls 1 and 2 and slightly spaced so that the ribbon R may pass therebetween vertically. These blocks are traversed by bores through which reciprocate 80 the horizontal punches 5 when they or some of them are actuated by the mechanism hereinafter to be described. The bores in the die block 4 enlarge as at the point 6 so as to 85 allow the free egress of the waste. 90

The punches 5, which are plural, there being shown eight (although it is not essential that there be just this number), are operated in the following manner: The punches are ordinarily held in a retracted 95 position, as shown in Fig. 12, by the spring 7, which is attached to the end of each punch. In connection with each punch is a punch-setter 8 which is a bell-crank arm that is pivoted on the shaft 9. On the lower 100 end of the bell crank arm or punch-setter 8 is pivoted a punch-actuator 10 whose upper end is contacted by a rubber covered buffer-rod 11 and whose lower end contacts the end of the punch 5. The spring 12 presses 105 against the punch-setter and ordinarily holds the punch setter in the position shown in the full lines of this figure and the punch actuator in the position shown in the full lines. However, when draft is made upon 110

the cord 13, that is attached to the upper arm of the bell-crank arm or punch-setter 8, the punch-actuator 10 is caused to rise to the position shown by the dotted lines in Fig. 12. This brings this actuator into the path 5 of the blade 14 which is attached to the cylinder 15 in a longitudinal groove in the cylinder for that purpose and which revolves clockwise. The cylinder 15 is revolved very 10 rapidly by the electric motor M so that the actuator 10 is actuated a great many times a minute when it has been set in operative position by draft on cord 13. This actuator 15 communicates the oscillations caused by the blade to the punch 5 and forces it across the path of the ribbon in rapid reciprocations, the punch being returned each time by the spring 7. The setting mechanism 20 may be adjusted by the screw 16 and lock-nut 17, so as to limit the amount of travel of the punch-setter 8 and hence regulate the thrusts of the punch-actuator 10 into the path of the blade 14 and therefore the action of the punch 5. Draft on the cord 13 is furnished by the magnet 18 which has a pivoted armature 19, one end of which is attached to the cord 13. This magnet 18 is wound by the wire 20 of an electric circuit which is broken at one point. This point 25 is the contact 21 (Fig. 7) when it engages with the insulated portion 22 of the disk. This disk is a return conductor for all the circuits that operate the magnets (see Fig. 4). This figure shows the operation of the 30 circuits diagrammatically, for instance, the circuits *a*, *b*, *c*, are closed as the terminals of the wires are in contact with the metallic portion of the disk through which the current may travel and return to the battery through the return wire 23. The remaining 35 terminals are in contact with the insulating portion of the pattern disk and hence these circuits are not closed and the magnets 18 connected with these circuits are not energized.

40 In Fig. 6 a detail of a portion of the disk pattern is shown. It will be seen that the insulating medium 22 is cut away, exposing a metallic portion of the disk that forms the letters "C," "B," "A."

45 Referring to Fig. 7, the construction of the contacts 21 will be seen. These contacts are in the form of a bell crank arm having at one end a pointed terminal 21^a that is adapted to travel on the under surface of the pattern disk. A hook 21^b is arranged to engage under the bar 24 which is insulated on its under side so as to limit the oscillation of the contact 21. The lower arm 50 of the contact 21 I prefer to make of piano wire and this has a sliding contact with the plug 25. However, the contact is never broken, and the sliding contact is provided, in order to allow of the movement of the 55 contact. Referring to Fig. 11, it will be

seen that these plugs which are inserted in the insulated block E are staggered so as to allow of a more compact arrangement.

When the pattern of a given letter (Fig. 6) is over the terminals 21^a (as shown in Fig. 10) it will be understood that all or a selected portion of the entire number of terminals will be engaging with the metallic portion of the disk and hence the circuits through these terminals will be closed and all or a selected number of the magnets 18 will be energized and all or a selected number of the punch-setters 8 will be drawn back and the corresponding punch-actuators 10 drawn into the path of the blade 14, hence the punches 5 connected with the actuators will be rapidly reciprocated.

The letters on the pattern disk are arranged along the edge as shown in Fig. 9. When it is desired to perforate any letter upon the ribbon, this letter is brought to a point adjacent the terminals of the contacts then the pedal 27 is depressed as shown in Fig. 4. This pulls downward the link 28 that is fastened to the presser arm 29, one end of this presser arm is pivoted to a post 30 and the other end carries a presser roll 31 which engages directly above the terminals 21^a, located underneath the disk and near this presser roller 31 is a feed roller 32 which is on the shaft 33, hence when the presser roller 31 is engaging the upper face of the disk, the turning of the shaft 33 by revolving the hand wheel 34 causes the disk to revolve about its center. Supporting 38 rollers are arranged about the edges of the disk at the points as shown in Fig. 9. Roller 35^c (Fig. 2) is in a slightly lower position than the rollers 35^a and 35^b and the center pin 37. The rollers 35^a and 35^b are each set about 100 degrees from roller 35^c and above the level of the center pin 37. This warps the disk 22, the natural spring of which keeps it in contact with roller 35^c until the lever 29 is depressed thus raising one edge 40 from the roller 35^c and depressing the opposite edge to engage with the contacts 21 and the actuating roller 32. When the disk is in its tilted plane and in contact with roller 35^c it may be revolved about its center so that any given letter may be placed above the contacts. When it is desired to operate the perforator, the pedal 27 is depressed which brings that letter into engagement with the terminals of the contacts and hence energizes the magnets which set the punch-actuators in the path of the revolving blade so that the dies may be reciprocated. Of course only those punches are reciprocated which are connected with the terminals that at a given period of time are in contact with the metallic portion of the pattern disk.

The revolution of the disk across the terminals is effected by the roller 32 which is fast to the shaft 33 that is turned by the

hand wheel 34. This shaft 33 also serves to feed the ribbon across the punches (Fig. 2). This is effected by a gear wheel 36 on the end of the shaft 33 that meshes with the 5 pinion 36^a on the end of the shaft that carries the upper feed roll 1. The roll 1 drives the idler roll 2 by friction therewith. The hand wheel 34 should be turned only at a moderate speed for if it is turned too rapidly, the ribbon will be fed through the dies so fast that they may not cut a smooth edged slot.

Referring to Fig. 4 it will be seen that the 15 pedal 27 engages a spring pressed plunger 40 which is ordinarily forced out of engagement with the spring terminal 41 by the spiral spring which encircles the plunger. This spacing of the plunger and the spring terminal 41 operates as a break in the circuit 20 which controls each of the magnets, hence the magnets are never energized so as to operate the punch-setters until the pedal 27 is completely depressed and brings the presser-roll into contact with the disk so 25 that the letter on the pattern may contact with the terminals. The motor is switched on and off by an ordinary electric switch which is not shown, and runs continuously while the machine is being operated.

30 The tape or ribbon R is carried on a storage roll S which is supported by a pair of brackets 42, and 42^a from the floor. 42^a is slightly higher than 42 to cause the ribbon to guide into the die blocks 4 and 5 with 35 the right hand edge always in contact with the right hand wall of the slot between the die blocks. This insures the ribbon always being alined to bring the perforations a given distance from the edge of the ribbon. 40 The letters upon the pattern disk are arranged so that those most commonly used are as close as possible together. They may also be arranged in groups which are most likely to occur in words so that the pattern 45 disk may be operated with the least possible revolution.

What I claim is—

1. A perforating machine, having in combination, a plurality of punches, a revolving member, an actuator for each punch adapted to be thrust into the path of the revolving member and means for selecting certain of the actuators to be thrust into the path of the revolving member, substantially as described.

2. A perforating machine, having in combination, a plurality of punches, a punch-actuator for each punch, a revolving member into the path of which the actuators may 60 be thrust, punch-setters for thrusting the punch-actuators into the path of the revolving member and selective means for controlling the punch-setters, substantially as described.

65 3. A perforating machine, having in com-

bination, a plurality of punches, springs for normally keeping the punches in retracted position, a revolving member, a pivoted punch-actuator for each punch, a punch-setter for carrying each punch-actuator and 70 thrusting it into the path of the revolving member and selective means for operating the punch-setters, substantially as described.

4. A perforating machine, having in combination, a plurality of punches, a punch-actuator for each punch, a revolving member into the path of which the punch-actuators are thrust to actuate the punches, a punch-setter in the form of a bell-crank arm for each punch-actuator and to which each punch-actuator is pivoted and selective 80 means for swinging the punch-setters or bell-crank arms to thrust the punch-actuators into the path of the revolving member and actuate the punches, substantially as 85 described.

5. A perforating machine, having in combination, a plurality of punches, individual means for controlling the actuation of each punch, means for rapidly and repeatedly 90 reciprocating the punches designated by the control means, a pattern and electrical connections between the pattern and the individual control means for each punch for selectively designating the punches in accordance with the design of the pattern, substantially as described.

6. A perforating machine, having in combination, a plurality of punches, individual means for controlling each punch, means 100 for rapidly and repeatedly reciprocating the punches designated by the control means, a pattern provided with a design desired to be cut in the ribbon and connections between the pattern and the individual punch, controlling means for selectively governing the action of the punches to form the design of the pattern, substantially as described.

7. A perforating machine, having in combination, cutting mechanism, selective means for controlling the operation of the cutting mechanism, a pattern disk provided with selectable characters and electrical connections between the pattern disk and the selective control means of the cutting mechanism for the transference of a selected character on the pattern to the ribbon, substantially as described.

8. A perforating machine, having in combination, cutting mechanism, selective means for controlling the action of the cutting mechanism, a plurality of electrical magnets and armatures for controlling the selective means, a pattern disk provided with selectable characters, electric circuits for energizing the magnets and adapted to engage with a selected character on the pattern disk to be broken or closed and thereby operate the selective means for governing the action of the cutting mechanism, substantially as described.

9. A perforating machine, having in combination, a plurality of punches, individual means for governing the operation of each punch, a plurality of electric magnets for selectively operating the individual governing means of the punches, an insulated pattern disk provided with cutaway portions to expose a conducting material representing characters that may be selected, a plurality of circuits for energizing the magnets and adapted to contact with the disk to alternately engage with the insulated portions and the conducting portions to break and close the circuits and operate the magnets to govern the action of the punches, substantially as described.
10. A perforating machine, having in combination, a plurality of punches, individual means for actuating each punch, a plurality of magnets for actuating the said individual means, a rotatable pattern disk insulated and having cutaway portions representing the designs desired to be impressed upon the ribbon and that expose conducting material and electric circuits for energizing the magnets, contacting with the disk when rotated to bring a selected design above the contacts of the electrical circuits whereby the circuits energize the magnets and operate certain selected punches, substantially as described.
11. A perforating machine, having in combination, cutting mechanism and an electric control therefor, comprising a pattern disk,

rollers for supporting the same revolvably and for warping the disk and depressing it normally at one of the sides of the disk, a plurality of electric circuits for controlling the cutting mechanism having contacts opposite the depressed side of the disk and a presser roller adapted to be brought into contact with the disk to depress it upon the contacts, substantially as described.

12. A perforating machine, having in combination, cutting mechanism, electric circuits for controlling the same, a pattern disk provided with insulated and conducting portions, contacts connected with said electric circuits, supporting rollers for supporting the disk revolvably and arranged to warp the same and depress one side of the disk, the said contacts being located diametrically opposite the depressed side of said disk, a presser roller for pressing the disk into engagement with the contacts when operation is desired, a pedal for controlling said presser roller, and a make and break in the common return wire of the circuits operated also by the depression of said pedal, substantially as described.

In testimony whereof, I sign this specification in the presence of two witnesses.

EVERETT H. BICKLEY.
